ROTARY DISK KNIFE

Arthur H. Ahrendt and Paul H. Meyer, La Porte, Ind., assignors to U. S. Slicing Machine Company, La Porte, Ind., a corporation of Indiana

Application April 21, 1944, Serial No. 532,052

1 Claim. (Cl. 146—95)

1 This invention relates to slicing knives and more particularly to a circular or generally disk-shaped slicing knife for use in slicing machines employing a rotary slicing knife for slicing substances such as meat and other materials.

An object of this invention is to provide durable, simple and efficient slicing means which will not rust, which will not stain or contaminate the substance sliced, which will retain a sharp cutting edge, and which, when dulled by use, may be ground to produce a new cutting edge with minimum effort and waste of material.

It has been the practice to employ carbon steel knives for such purposes, plating the knives to avoid rust and for hygienic reasons. The plating operation involves the exercise of considerable care, and entails labor and expense. Unless done very carefully the plating peels and the knife becomes susceptible to rust. The ground edge of such a knife, moreover, is always exposed to rust as the grinding operation results in the grinding off of plating material. The manufacture of carbon steel knives also entails waste of steel for the hardening of such material usually results in warping of the material, necessitating the provision of a billet large enough and thick enough to enable the elimination of the warp by a turning operation on a lathe. The structural requirements of generally disk-like knives of carbon steel dictate the provision of increased thickness of the knife adjacent the cutting edge with the result that in the grinding of such knives when dull there is either increased waste of material or undesired enlargement of the beveled surface adjacent the cutting edge.

The present invention overcomes the disadvantages incident to the manufacture of slicing knives of carbon steel in the use of stainless steel. This may be provided in the form of a generally round, flat blank of approximately the desired thickness, which may be shaped to generally disk-like or dish form on a punch press and reinforced by the addition of a central stiffener or reinforcing plate which is spot welded in place. Thereafter the peripheral portion of the disk may be hardened and ground to provide a durable cutting edge, reserving a generally soft or unhardened center which is not subject to deflection or deformation to the same extent as the conventional, hardened carbon steel knife.

Another object of this invention is to provide a generally disk-shaped slicing knife having a hardened peripheral portion with opposite surfaces arranged in parallel relation with one another and a beveled periphery comprising a cut-

ting edge, the cutting edge preferably being at one of the parallel surfaces.

A further object of the invention is the provision of such a knife arranged to be mounted for rotation about an axis normal to a surface of its central portion and having such a hardened peripheral portion disposed in angular, radially spaced relation with the said axis and a peripheral bevel disposed in angular relation with the parallel surfaces.

An additional object of the invention is to provide a slicing knife having a dish-shaped body, an annular peripheral portion, and an inclined portion connecting the body and the annular portion.

Other objects of the invention include the provision in a slicing knife having a peripheral portion of generally uniform thickness and a cutting edge with a generally uniform bevel, which may be sharpened from time to time with a minimum of labor and waste of material to provide a new cutting edge of substantially like form and dimensions; the provision of such a knife with a body of substantially uniform thickness and an annular peripheral portion of reduced, substantially uniform thickness; the provision of such a knife with an angular intermediate portion of reduced, substantially uniform thickness.

Additional objects, advantages and capabilities inherent in this invention will become readily apparent from the description thereof which follows.

This invention further resides in the combination, construction and arrangement of parts illustrated in the accompanying drawings, and while there is shown therein preferred embodiments of the invention, it is to be understood that the same are susceptible of modification and change without departing from the spirit of the invention.

The accompanying drawings illustrate a selected embodiment of the invention, and the views therein are as follows:

Fig. 1 is a plan view of a slicing knife embodying the invention;

Fig. 2 is a central, sectional view of the knife shown in Fig. 1;

Fig. 3 is a fragmentary, sectional view of a reinforced blank employed in forming a knife embodying the invention; and

Fig. 4 is a fragmentary view of the blank shown in Fig. 3 after being ground to form, with original outlines of the blank indicated in dotted lines, and additional angular dotted lines indicating cutting edges resulting from regrinding from time to time.

The particular knife 10 herein disclosed for the

purpose of illustrating the invention comprises a generally disk-like body 11 which, as shown, is of stainless steel and provided with a central, reinforcing plate 12 spot welded thereon. A central opening 13 co-axial with the body 11 and the plate 12 is provided for mounting the knife on a shaft of a slicing machine for rotation.

The body 11 and the plate 12 may be formed from flat disks of stainless steel which are shaped in a punch press, the plate 12 being shaped to the form shown in Fig. 2 and the body 11 being shaped to provide a peripheral portion 14 of the form shown in Fig. 3 and indicated in dotted lines in Fig. 4.

Thereafter the peripheral portion 14 of the knife is hardened and then ground to the form shown in Fig. 4, the waste or ground off portion being indicated in dotted lines in that figure. The grinding of the peripheral portion of the body 11 of the blank shown in Fig. 3 is conducted to produce a portion of desired thickness, which may be of the order of .048" to .050", with opposite, preferably parallel surfaces 15 and 16, a peripheral bevel 17, and an adjacent cutting edge 18. The hardened portion of the knife, including the surfaces 15 and 16, extends inwardly from the cutting edge 18 a substantial distance to provide for repeated grinding of the cutting edge to provide new cutting edges, as indicated by the dotted angular lines in Fig. 4, with beveled portions 17 of like dimensions and angular relation with the original beveled portion.

The knife 10 thus produced is generally disk-shaped with a depressed central portion 19 having opposite surfaces 20 and 21 disposed in planes substantially normal to the axis 22 of the opening 13, intermediate portions 23 and 24 arranged in angular, radially spaced relation with the axis 22 and with one another, a peripheral portion having opposite surfaces 15 and 16 parallel with one another and disposed in angular, radially spaced relation with the axis 22 and the intermediate portions 23 and 24, and a peripheral bevel 17 disposed in angular relation with the surfaces 15 and 16 and providing a circular cutting edge 18.

The formation of a slicing knife in the manner stated, using stainless steel, enable the provision of a knife having a bevel approximately $\frac{1}{8}$ " wide adjacent the cutting edge and the maintenance of a bevel of like width through successive regrinding operations until the available hardened portion of the knife, which ordinarily will extend a depth of $\frac{3}{4}$ " inwardly from the cutting edge of the knife, is exhausted.

An example of a slicing knife embodying the invention which has been found satisfactory may be described as follows: A flat disk of stainless steel $\frac{1}{8}$ " thick is centrally reinforced by welding thereon a circular plate of like material $\frac{3}{32}$ " thick. The composite article is shaped in a punch press to generally dish form, as shown in Fig. 3, with a substantially flat central portion of approximately 3" in diameter, an adjacent, intermedi-

ate annular portion approximately 5" wide and having an outer diameter of approximately $9\frac{3}{4}$ ", an annular peripheral portion approximately $1\frac{1}{8}$ " wide and having an outer diameter of approximately $11\frac{1}{4}$ ", and an angular portion connecting the said peripheral portion and the said intermediate portion and having opposite surfaces arranged in parallel relation with one another and disposed at an angle of approximately 30° with the said surface of the central portion. The peripheral portion is hardened by induction. The peripheral portion and the adjacent connecting portion are then ground to the form shown in Fig. 2, providing a connecting portion having opposite, parallel surfaces spaced approximately $\frac{1}{16}$ " apart, a peripheral portion having opposite, parallel surfaces spaced approximately .050" apart and disposed at an angle of approximately 2° in relation to a plane parallel with the said surface of the central portion, and a peripheral bevel approximately $\frac{1}{8}$ " wide to provide a cutting edge at the upper surface of the said peripheral portion, viewing Fig. 2.

Changes may be made in the form, construction and arrangement of the parts without departing from the spirit of the invention, and the right is hereby reserved to make all such changes as fairly fall within the scope of the following claim.

30 The invention is hereby claimed as follows:
A circular knife for meat slicing machines and the like comprising an outer peripheral thin circular rim having straight, flat, parallel sides extending in a direction perpendicular to the axis of the knife and terminating in a cutting edge, an inner integral section extending from the inner end of the rim at an angle from the plane of the rim and having parallel sides, a dish shaped central portion extending inwardly from the inner section and integral therewith, said central portion increasing in thickness toward its center, and a central circular reinforcing section fixed to the concave part of the central dish shaped portion and conforming in shape thereto and of less diameter.
